CHARLES FREDERICK GREEN, OF HORNCHEWCHURCH, ENGLAND, ASSIGNOR TO A. B. DICK COMPANY, OF CHICAGO, ILLINOIS, A CORPORATION OF ILLINOIS.

STENCILING MATERIAL.

1,127,986.

Specification of Letters Patent.

Patented Feb. 9, 1915.

Application filed November 18, 1913. Serial No. 300,893.

To all whom it may concern:

Be it known that I, CHARLES FREDERICK GREEN, a subject of the King of Great Britain, residing at Northfield, Herbert 5 Road, Hornchurch, Essex, England, have invented certain new and useful Improvements in Stenciling Material, of which the following is a specification.

The object of the present invention is to 0 improve upon stencil-sheets of the character heretofore commonly used, with respect to means for increasing the durability of such sheets in service. Composite stencil-sheets heretofore employed are usually made up of 5 a protecting tissue, a waxed or otherwise treated sheet of porous paper and a relatively stiff and hard backing. In these, it has been common to provide the "backing-sheet" with a line of perforations a short 10 distance from the forward edge of the sheet and along which line the major part of the backing-sheet may be torn after the sheet has been positioned upon the drum of the duplicator, so as to permit the ink to be 15 passed therethrough. I have found that the severing of the backing-sheet by means of this line of perforations leaves a rough or saw-tooth edge to that portion of the blank which is a permanent part of the composite stencil-sheet, and that under the influence of the pressure-roller this is pressed 20 so firmly and so frequently against the stencil-sheet as eventually to weaken the sheet at the point of contact. I, therefore, provide 25 the composite stencil-sheet of this invention with a separate interleaving sheet of such length as to extend beyond the line of perforations along which the backing-sheet is to be severed and therefore to interpose a cushion between the severed forward 30 portion of the backing-sheet and the stencil-sheet lying next adjacent thereto.

In the drawings, Figure 1 is a plan view of the drum of a duplicator, illustrating the 35 button-bar commonly used for coaction with the forward edge of the stencil-sheet; Fig. 2 is a central cross-section thereof; Fig. 3 is an inverted plan view of the forward portion of a composite stencil-sheet embodying 40 this invention; and Fig. 4 is a central longitudinal section thereof.

Referring to these drawings, it will be seen that the duplicator-drum is provided with a button-bar A, provided with suitably

spaced buttons or studs a, a, for coaction 51 with the stencil-sheet. The bar A is spaced a sufficient distance from the periphery of the drum to permit the stencil-sheet to be passed between the button-bar and drum and the buttons or studs a extend through 60 the button-bar and into the drum, so as to permit them to coact in manner hereinafter stated with the forward edge of the stencil-sheet.

The stencil-sheet as here shown is of the 65 "composite" variety and comprises the protecting tissue B, the stencil proper C and the backing-sheet D. The protecting tissue is desirable when a stencil-sheet provided with a waxlike coating is employed, which 70 is capable of being removed by the impact of the type. It may be dispensed with when employing stencil-sheets such as are now in common use, provided with a coating of coagulated protein. The backing-sheet D is 75 provided adjacent to its forward edge with a line of perforations d. At its extreme forward edge, I preferably secure thereto a reinforcing sheet d' of such width as to extend over the backing-sheet to a point 80 rearward of the line of perforations d. As will be seen, therefore, when the major portion of the backing-sheet D is severed along the line of perforations d, the reinforcing sheet d' will overlie the roughened edge of 85 the forward portion of the backing-sheet, so as to interpose a cushion between such roughened edge and the stencil-sheet C which immediately overlies it.

The stencil-sheet C, and preferably the 90 protecting tissue B, are secured, preferably by adhesives, to the reinforcing sheet, as shown, or if desired directly to the backing-sheet, either at its extreme forward edge or at a point intermediate of the same and the 95 line of perforations d.

The extreme forward edge of the composite stencil-sheet here described is preferably provided with a series of openings corresponding in number and spacing to the 100 buttons or studs upon the button-bar A. These openings comprise notches e, preferably of such size as to snugly receive the buttons or studs a, and, communicating with such notches, recesses e', the open forward 105 ends of which are preferably of somewhat greater width than the diameter of said buttons or studs.

In order to secure the stencil-sheet in position upon the drum of the duplicator, it is necessary only to place the forward edge of the stencil-sheet adjacent to the button-bar 5 and between the same and the surface of the duplicator-drum, and then press the said sheet forward until the buttons or studs a enter the recesses e' to the full extent of such recesses. Then a lateral movement 10 will bring the buttons or studs a into the notches e , whereupon a rearward movement of the stencil-sheet will bring said buttons or studs into coaction with the forward portions of the notches e , permitting sufficient pressure to be brought upon the stencil-sheet 15 to enable the same to be firmly and smoothly secured to the periphery of the duplicator drum. This operation may be more quickly and easily accomplished than 20 is possible where the forward edge of the stencil-sheet is provided with closed slots. Moreover, it is unnecessary, as in the case of the latter, to successively bring a slot and a button or stud into coaction, the few and 25 simple movements described assuring coaction of all the buttons or studs and all of the recesses and notches as part of the same operation.

The reinforcing member d' , in addition to 30 protecting the stencil-sheet C against injury from the roughened edge of the forward portion of the backing-sheet, also desirably strengthens the forward edge of the composite sheet at the point of contact with the 35 pressure-roller of the duplicator.

Having now described my invention, what

I claim as new therein and desire to secure by Letters Patent is as follows:—

1. A composite stencil-sheet comprising a backing-sheet having a line of transverse 40 perforations near one end, imperforate stencil and reinforcing sheets, secured to said backing-sheet between the end thereof and the adjacent perforations, said reinforcing sheet being interposed between said backing 45 and stencil-sheets and of a length sufficient to extend a short distance over said line of perforations, to form a cushion between the same and said stencil-sheet when said backing sheet has been torn off on said perforations, substantially as set forth.

2. A composite stencil-sheet comprising a backing-sheet having a line of transverse perforations near one end, a reinforcing sheet secured to said backing sheet between 55 the said end thereof and the said perforations, and being of a length sufficient to extend a short distance over said perforations, and a stencil sheet extending over said perforations and over said reinforcing sheet, 60 the latter being adapted to form a cushion between said stencil-sheet and said perforations when said backing sheet has been torn off on said perforations, substantially as set forth.

This specification signed and witnessed this 29th day of October, 1913.

CHARLES FREDERICK GREEN.
